ATTORNEY

UNITED STATES PATENT OFFICE.

SAMUEL HERBERT MALPAS, OF INDIANAPOLIS, INDIANA, ASSIGNOR TO
JACOB L. BIELER, OF INDIANAPOLIS, INDIANA.

AUTOMATIC GAS-LIGHTER.

SPECIFICATION forming part of Letters Patent No. 724,027, dated March 31, 1903.

Application filed March 29, 1901. Serial No 53,544. (No model.)

To all whom it may concern:

Be it known that I, SAMUEL HERBERT MALPAS, a citizen of the United States, residing at Indianapolis, in the county of Marion and State of Indiana, have invented certain new and useful Improvements in Automatic Gas-Lighters, of which the following is a specification.

My said invention relates to an apparatus for automatically igniting gas-jets; and it consists in the construction and arrangement of parts hereinafter particularly described and claimed.

Referring to the accompanying drawings, which are made a part hereof, and on which similar reference characters indicate similar parts, Figure 1 is a side elevation of an automatic gas-lighter embodying my said invention, a portion of the handle-rod being broken away; Fig. 2, a central sectional view thereof, the shield being omitted and (for purposes of clearness) its position being indicated by means of dotted lines only; Fig. 3, a detail sectional view on the dotted line 3 3 in Fig. 1, and Fig. 4 a detail sectional view on the dotted line 4 4.

This device has a handle-rod 1, preferably in the form of a metal rod or heavy wire, which terminates in the grip 2, which is commonly made of wood. The opposite end of said handle-rod extends to one side and is securely united to a hub-like portion 3, which forms the base of the lighter proper. At the point where it is bent a yoke-piece 4 is secured, which is of a suitable form to engage with and operate the gas-key in turning on and shutting off the gas. This part 4 has a central perforation, down through which the handle-rod 1 extends, and it may be secured rigidly in place by any suitable means, as by a rivet 5. It also preferably has a projection 6, which is adapted to hook over a nail or pin when the gas-lighter is hung up, this serving to confine the nail or pin to a point next to the handle-rod.

The hub-like portion 3 has a central perforation to receive the base of the lighting device, which I have denominated a "cartridge." This cartridge is composed of this base 7, a

standard 8, and a wire or filament 9, extending from the base to an arm on the upper end of the standard and at a little distance from the body of said standard, as shown, this fine wire or filament being composed of a peculiar metal and having secured thereon particles 10 of a peculiar chemical composition, said composition being of such a character that when the apparatus is inserted in a flow of ordinary illuminating-gas such a chemical action will take place as will ignite the gas.

This lighter or cartridge is inclosed and protected by a shield 11, which is in form a shell of suitable size containing numerous perforations and open at one end. This open end or neck is of a size and form adapted to fit over the hub 3 and be there secured by a screw 12, which passes through the neck of this shield and into the screw-threaded perforation in said hub 3, its point impinging against the cartridge and serving as a setscrew to hold it in place. In operation when the filament becomes destroyed this screw is simply removed, when both the shield can be taken off and the cartridge taken out, the cartridge renewed and the shield replaced, all as will be readily understood. In an apparatus of this character a shield is highly necessary, as the igniting-filament is small and slender, of slight strength, and consequently, unless protected, will become broken very frequently and the usefulness of the apparatus thus destroyed, while when protected by such a shield it will under ordinary circumstances last for a considerable period and when it fails or becomes broken is easily removed. At the same time, while the shield is to be removable for the purposes stated, it should be so securely mounted as not to be easily taken off by merely curious persons, as such removals and replacements endanger the delicate filaments. The screw 12 is therefore driven in quite tightly.

Having thus fully described my said invention, what I claim as new, and desire to secure by Letters Patent, is—

An automatic gas-lighter comprising a handle-bar having a portion bent to one side, a yoke-piece having a perforation through

which said bar passes, said yoke-piece being secured to said handle-bar at the bend therein and adapted to serve as the means for turning the gas-key, and a suitable lighting-cartridge secured to the outer end of said bar, all substantially as set forth.

In witness whereof I have hereunto set my

hand and seal, at Indianapolis, Indiana, this 27th day of March, A. D. 1901.

SAMUEL HERBERT MALPAS. [L. S.]
